(57) **CLAIM**

The ornamental design for an inflator pump as shown and described.

DESCRIPTION

FIG. 1 is a bottom end perspective view of the inflator pump.

FIG. 2 is a top end perspective view of the inflator pump.

FIG. 3 is a front side view of the inflator pump.

FIG. 4 is a rear side view of the inflator pump.

FIG. 5 is a left side view of the inflator pump.

FIG. 6 is a right side view of the inflator pump.

FIG. 7 is a bottom end view of the inflator pump; and,

FIG. 8 is a top end view of the inflator pump.

The portions shown in broken lines form no part of the claimed design.
